UNITED STATES PATENT OFFICE.

AUGUSTUS FREDERIC BROWN, OF HAVRE DE GRACE, MARYLAND, ASSIGNOR TO GORRELL STEEL SPIKE LOCK RAILROAD TIE CORPORATION, OF HAVRE DE GRACE, MARYLAND, A CORPORATION OF MARYLAND.

METALLIC RAILWAY-TIE.

1,158,975.

Specification of Letters Patent.

Patented Nov. 2, 1915.

Application filed August 20, 1915. Serial No. 46,532.

To all whom it may concern:

Be it known that I, AUGUSTUS F. BROWN, a citizen of the United States, residing at Havre de Grace, in the county of Harford 5 and State of Maryland, have invented certain new and useful Improvements in Metallic Railway-Ties, of which the following is a specification.

My invention relates to certain new and 10 useful improvements in metallic railway ties and rail fastenings and particularly ties formed of substantially similar sections of pressed steel or like metal, as disclosed more fully in my former Patent No. 1,127,350, 15 dated February 2, 1915.

The leading object of the present invention is to supply a tie substantially of the character before mentioned, with means whereby spike-receiving recesses may be 20 formed in separate sectional boxes whose components are rigidly secured to the sections of the tie and have their inner edges fashioned sinuous or with alternate projections and depressions to form therebetween 25 a vertical channel of substantially serpentine shape for the reception and distortion of the spikes which are employed to secure the rails to the tie.

With the above and other objects in view, 30 my invention consists of the parts and the constructions, arrangements and combinations of parts which I will hereinafter describe and claim.

In the accompanying drawings forming 35 part of this specification and in which similar reference characters indicate like parts in the several views; Figure 1 is a side elevation of a railway tie embodying my invention, showing one end of one of the sections broken away. Fig. 2 is an enlarged similar view of one end of a modified form. Fig. 3 is a cross-sectional view on the line X—X of Fig. 2. Fig. 4 is a detail to be referred to.

45 In said drawing A represents a railway tie formed entirely of metal and, preferably, of two similar sections, A'—A², of pressed steel or the like, each of said sections comprising a transverse bottom flange, a, of suitable width, and a flange, b, which, when the tie is in position, extends perpendicu-

larly to the flange, a, and rises from the inner edge thereof and extends from end to end of the tie.

The two sections, A'—A², of the tie are 55 similar in character and construction and they are adapted to be joined together in some appropriate manner. This may be done as in the before mentioned patented construction by providing one of the sections with a pin or post, 10, which extends transversely from its inner surface and is designed to enter and extend through a corresponding opening, 12, formed in the flange portion, b, of the other section, the projecting portion of the pin or post being then headed down to unite the sections, or, if desired, the projecting portion of the pin or post may be threaded to receive a suitable nut, as in Fig. 4. 70

For the sake of lightness and at the same time to give added strength to the tie, the vertical flanges, b, of the sections, A'—A², thereof may be formed with openings, c, at the ends and intermediate portions, as is 75 well known in this art.

The upper portion of the vertical flange, b, of each section of the tie is widened transversely by forming the section with horizontal flanges, d, one near each end, 80 which flanges are designed to match and to extend for a suitable distance along the upper edge of the section whereby when the two sections of the tie are fitted together, the horizontal flanges, d, form seats and 85 supports, e, for the usual railway rails, B.

At one or both sides of the rail seats, e, the vertical flanges, b, and horizontal flanges, d, of the sections of the tie are formed integrally or otherwise provided with vertically matching shoulders, f, which engage the horizontal base flange of the rails, B, and by which lateral spreading of the rails is prevented. 90

In order to practically and efficiently supply the pressed sections of the tie with means for receiving and at the same time distorting the spike which secure the usual rails to the tie, and to securely lock the spikes in place, I press or fashion the inner face of 100 each tie-section at each side of the rail seat with a depression to receive a suitable spike

lock plate or bar, 20, which plates are preferably made from rolled steel, as stampings, and which are riveted or otherwise rigidly secured to said section.

5 The inner edges of the lock plates or bars, 20, are formed undulating; that is, with alternate elevations and depressions, 21, which may merge one into the other to give a continuous serpentine form to a spike receiving 10 channel, 22, which is formed by the proper spacing of the inner edges of the lock plates or bars from each other, said channel being open at the top and bottom, and the length of the lock plates or bars being about equal 15 to the height of the vertical flange, *b*, of the tie, and which lock plates or bars of one section of the tie will stand opposite similar plates or bars secured to the opposing tie section so that the space formed between the 20 inner edges of a pair of the plates or bars on one section will match the like space formed between the inner edges of the plates or bars of the other section to form the complete serpentine channel into which the 25 spike is driven and by the undulating edges of the lock plates or bars will be distorted and converted from its normal straight form into one which conforms to the shape of the channel. This distortion of the spike also 30 results in its being self-locking during the driving operation, as described in my aforesaid prior patent.

The form of the spike receiving channels may vary within reasonable limits without 35 departing from the spirit of the present invention. For instance, in Fig. 2, the inner edge of one of the lock plates or bars, 30, is formed with the curved ribs 31 and the corresponding edge of the companion lock 40 plate or bar is formed with recesses which stand opposite the ribs of the first mentioned lock plate or bar. In either case, a normally straight spike of any desired cross-section and of a diameter only slightly less than 45 that of the channel formed between the inner edges of the lock plates or bars, when forcibly driven into the channel formed therebetween will be distorted and made to conform to the shape of said channel, and 50 at the same time locked in place without the aid of other or supplementary fastenings.

As there is liable to be some variableness between the spikes used and the fixed diameter of the channel designed to receive the 55 same, I show in Fig. 2, a construction which provides for this and obviates all possibility of vibrations in a direction at right angles to the plane of the distortion resulting from 60 the spike being driven past the curved ribs or projections, 31. To this end, I press the sections of the tie at points corresponding to the space formed between the inner edges of the spike lock plates or bars, with inner 65 bosses, 33, which alternate with each other

and with the ribs or projections, 31, and which are designed to distort the nail or spike while the same is being driven into its seat in the socket, in a plane substantially at right-angles to that in which it is bent 70 by the ribs or projections, 31. By alternating the projections, or bosses, 33, and not having these projections or bosses disposed diametrically opposite each other, depressions are formed in one side of the nail or 75 spike and corresponding projections are offset from the opposite side, and which projections fill the transverse space between the straight portions of the sides of the spike or nail and the corresponding portions of the 80 walls adjacent thereto whereby the nail or spike is made to closely fit the socket or nail aperture transversely, and the nail or spike is thus prevented from having any lateral or transverse vibration or movement, 85 and which movement is objectionable especially when the spike is used for securing a railroad rail to a metal tie, or where one part is designed to be so rigidly secured to another that lateral vibration would be a 90 detriment.

In either of the described constructions, the spike lock pieces form substantially open-ended boxes having undulating spike receiving channels, and these boxes by being made up of the separate rolled or stamped pieces with fashioned inner edges, may be readily riveted or otherwise fixedly secured to the inner sides of the pressed sections of the tie and thus enable me to reinforce the relatively thin walls thereof sufficiently to make possible in a pressed steel tie the provision of practical means for receiving the spikes and effecting their described distortion in two directions during 100 the driving operation.

When it is desired to adjust the rails transversely to take up or compensate for wear of the treads of the rails I employ suitable metal shims, D, which may be normally straight and which are placed in the opening against one of the sinuous walls thereof whereby upon driving the spike in place the shim is crowded against and into the curvatures of the wall, and is thereby so 115 distorted as to make it conform substantially to the wavy surfaces thereof, as shown in Fig. 1; at the same time the spike which is confined between the shim and the opposite sinuous wall of the opening is distorted 120 and made to conform substantially to the formation thereof and also to that of the distorted shim. The pressed steel sections may also be formed along their upper outer sides with a strengthening rib, 14, which extends substantially from end to end of the sections, as shown in Fig. 1.

The described tie is light and yet strong; it is comparatively inexpensive, and it will be found an excellent substitute for the or- 130

dinary wooden tie, as also for the metal and composite tie now used for similar purposes.

Having thus described my invention what I claim as new and desire to secure by Letters Patent is:

1. A metallic railway-tie formed of similar sections of pressed metal each having a vertical flange extending longitudinally thereof and being formed integrally with a part of a rail seat, each of said sections having pairs of separate plates secured to their inner surface, substantially at opposite ends of each rail seat, said plates of each pair having their inner edges spaced from each other and formed with alternating projections and depressions and the pairs of plates of one section adapted to register with the pairs of plates of the other section to form therewith spike receiving channels of irregular form adapted to distort and lock in position normally substantially straight spikes when the latter are driven into said channels in engagement with the undulating inner edges of said plates.

2. A railway-tie formed of similar sections of metal each of said sections having a rail seat near each end, and pairs of separate plates secured to the inner surface of each section near the ends of the rail seats thereof, the plates of each pair having their inner edges spaced from each other and formed with projections and depressions so arranged that the projections on the edge of one plate will stand opposite the depressions in the edge of the companion plate, the pairs of plates on opposed sections of

the tie substantially matching and the spaces between the inner edges of matching pairs of plates jointly forming spike receiving channels of irregular form adapted to distort spikes driven forcibly into said channels in contact with the formed inner edges of the plates.

3. A railway-tie formed of similar sections of pressed metal each formed with a portion of a rail-seat, said sections each having pairs of separate plates fixed to the inner surfaces thereof and the plates of each pair having inner edges spaced from each other and formed with alternate projections and depressions, the spaces between the inner edges of opposed pairs of plates jointly forming a spike-receiving channel of irregular form adapted to distort a spike driven forcibly therewith in contact with the inner edges of the plates, and said tie sections being pressed with bosses on their inner surfaces extending at right angles to the projections on the inner edges of the plates, said bosses being alternately arranged on opposite walls of the spike receiving channel and adapted to distort the spike laterally during the driving thereof, and to form projections on those sides of the spike which are at right angles to the sides engaged by the edges of the plates, said last-named projections adapted to fill voids in the spike channel and thereby prevent lateral vibration of the driven spike.

In testimony whereof I affix my signature.

AUGUSTUS FREDERIC BROWN.

Correction in Letters Patent No. 1 158,975.

It is hereby certified that the name of the patentee in Letters Patent No. 1,158,975, granted November 2, 1915, for an improvement in "Metallic Railway-Ties," was erroneously written and printed "Augustus Frederic Brown," whereas said name should have been written and printed *Augustus Freeborn Brown*; and that the said Letters Patent should be read with this correction therein that the same may conform to the record of the case in the Patent Office.

Signed and sealed this 7th day of December, A. D., 1915.

[SEAL.]

R. F. WHITEHEAD,

Acting Commissioner of Patents.
